UNITED STATES PATENT OFFICE.

DENTON E. PLUMLEE AND ANDREW E. GRUBER, OF SEGO, UTAH.

STAMP-AFFIXING MACHINE.

1,405,324.

Specification of Letters Patent. Patented Jan. 31, 1922.

Application filed December 21, 1920. Serial No. 432,280.

To all whom it may concern:

Be it known that we, DENTON E. PLUMLEE and ANDREW E. GRUBER, citizens of the United States, residing at Sego, in the 5 county of Grand and State of Utah, have invented certain new and useful Improvements in a Stamp-Affixing Machine; and we do hereby declare the following to be a full, clear, and exact description of the invention, such as will enable others skilled 10 in the art to which it appertains to make and use the same.

The object of the invention is to provide a relatively simple and comparatively inexpensive mechanism whereby postage stamps 15 may be applied to letters or envelopes containing letters with accuracy and expedition to avoid the inconvenience and loss of time incident to the manual application of the 20 same; and with these objects in view the invention consists in a construction and combination of parts of which a preferred embodiment is shown in the accompanying drawings, wherein:

25 Figure 1 is a side view of the machine.

Figure 2 is a front view of the same.

Figure 3 is a vertical section on the plane indicated by the line 3—3 of Figure 2.

Figure 4 is a vertical section on the plane 30 indicated by the line 4—4 of Figure 1.

Figure 5 is a detail sectional view on the plane indicated by the line 5—5 of Figure 1.

Figure 6 is a detail view of the cam by which the envelope clamps are actuated.

35 Figure 7 is a detail sectional view on the plane indicated by the line 7—7 of Figure 4.

Figure 8 is a view of the drum to show the arrangement of one of the envelope clamps thereon.

40 Figure 9 is a detail longitudinal section of the moistening roll to show the means by which the surface thereof is supplied with water.

The apparatus consists essentially of a 45 drum 10 arranged in cooperative relation with a hopper box 11 in which the envelopes to be stamped are arranged flat-wise or in parallelism in a tier or pile, so that the lowermost envelope is within engaging relation with a feed slide 12 located in the bottom thereof; a stamp affixing or depressing plunger 13 operatively connected with the drum 10; a stamp reel 14 adapted to contain a continuous strip of stamps as indicated at 15, and stamp feeding and

moistening mechanism indicated generally at 16.

In the illustrated embodiment of the invention, the shaft 17 of the drum is mounted upon a suitable frame work including 60 standard 18 and carries a gear wheel 19 meshing with a pinion 20 having a wrist pin 21 which is connected by a pitman 22 with the stem 23 of the plunger 13 which plunger operates in a vertical guide 24 accessible to the strip of stamps through an inlet slot 25 having a cutting edge 26 for cooperation with a cutting edge 27 on the follower, so that as the stamps are successively fed forward into the guide 24 and are 70 thus brought into the path of the plunger, the descent of the latter due to the rotary movement of the pinion 20 causes the separation of said stamp from the strip by the cooperative action of the cutting edges, and 75 the depression of the stamp into contact with an envelope located upon the surface of the drum 10.

The drum carries a series of fingers or tappets 28 for engagement successively with 80 a trip 29 which is connected with the slide 12, so as to advance the slide and by engagement with the lowermost envelope in the hopper box draw the same forward toward the guide 24, the return of the slide after 85 each actuation being effected by means of the spring 30. Also carried by the drum is a clamp 31 actuatable by a cam 32 which is supported by the standard 18, so that as each envelope is drawn out of the hopper it is 90 caught by the clamp and thus carried on the surface of the drum into the path of the plunger 13 operating in the guide 24.

Connected operatively with the shaft of the drum and mounted upon suitable lateral arms 33 of the standard are the cooperative feed rolls 34 and 35 connected by intermeshing gears 36 and 37 of which the latter receives motion from a gear 38 on a moistening roll 39 with which cooperates an idle or gravity actuated pressure roll 39'. The moistening roll receives rotary motion through a chain 40 traversing sprocket wheels 41 and 42 which are secured respectively to the main shaft 17 and the spindle 95 of the moistening roll. Said spindle of the moistening roll is preferably hollow as shown at 43 and in communication with the bore thereof is a water feed tube 44 leading from a water tank 45. The moistening roll 100

105

110

is preferably of an absorbent material and the moisture fed to the spindle thereof is taken up and conveyed through capillary action to the surface thereof over which the 5 strip of stamps, fed forward between the feed rolls 34 and 35, passes, being held firmly in contact therewith by the gravity pressure roll 39 so that the stamps are successively presented in the guide 24 in a properly moistened condition and properly positioned to be depressed by the plunger into engaging contact with the surfaces successively of the envelopes as they are presented thereto by the movement of the drum 10 and the parts 10 15 which cooperate therewith as hereinabove described.

Obviously any preferred means or power may be employed for communicating rotary motion to the shaft 17 of the drum, and with 20 the hopper properly stocked with the envelopes to be stamped it will be obvious that the operation of the mechanism will result in the successive presentation of the envelope to the affixing means with which cooperates 25 the stamp feeding devices serving to successively present the stamps in a properly moistened condition to be affixed to the envelope successively.

In the construction illustrated the envelope feed slide 12 is mounted in a guide frame 46 secured to the envelope hopper or box and is provided with a finger 47 operating in a slot 48 in the bottom of the box (shown clearly in Figure 5), and the trip 29 is adjustable with relation to the feed slide 12, in order to present the envelopes successively in properly timed relation with the movements of the other parts, and particularly of the stamp impressing plunger, by means 40 of a stem 49 secured at the proper adjustment by means of a set screw 50.

Also in order that there may be no sliding contact between the plunger and the stamps as the rotation of the drum, carrying the envelope, continues after the stamp is brought 45 into contact with the surface of the envelope, the plunger is preferably provided as indicated in detail in Figure 7 with a head 51 having an endless movable bearing face 50 formed by a belt 52 traversing idle rolls 53 and adapted to receive a progressive movement by contact with the stamp as the envelope with the stamp attached thereto moves forward under the impulse of the 55 drum. The doubling or tearing or distortion of the stamp after the plunger comes in contact therewith is thereby avoided.

Moreover, in order to provide for properly feeding envelopes of different sizes the 60 hopper is provided with gages 54 and 55 consisting of yielding or spring arms 56 having slotted bases 57 engaged by set screws 58. These gages as indicated are arranged respectively at one end and one side of the 65 hopper.

Having thus described the invention, what we claim is:

1. A stamp affixing machine having a revoluble drum, a feed hopper for envelopes, envelope feeding mechanism including a slide for successively engaging and advancing the envelopes from the hopper to the surface of the drum, tappets carried by the drum for successively actuating said slide, a plunger operatively connected with the 75 drum for radial movement toward and from the surface of the drum, and stamp feeding and moistening mechanism for successively presenting the stamps in the path of the plunger. 80

2. A stamp affixing machine having a revoluble drum, reciprocatory means for successively feeding envelopes to the periphery of the drum, a clamp to successively move into engagement with the envelopes 85 as they are presented upon the surface of the drum by said means, a plunger operatively connected with the drum for radial movement toward and from the surface thereof, and stamp feeding and moistening mechanism for successively presenting stamps in the path of the plunger. 90

3. A stamp affixing machine having a revoluble drum, reciprocatory feeding means for successively presenting envelopes to and arranging the same upon the periphery of the drum, clamping means engageable with the envelope after projection by said means for holding the envelopes on the drum, a plunger operatively connected with the drum 95 for movement toward and from the surface thereof, means for supplying a strip of stamps, feed rolls operatively connected with the drum for feeding the stamps to present the same successively in the path of the 100 plunger, means actuatable by the plunger for successively severing the stamps from the strip, and stamp moistening means arranged in the path of the stamps as they are fed to the plunger. 110

4. A stamp affixing machine having a revoluble drum, envelope feeding means for successively presenting envelopes to and placing the same upon the surface of the drum, a plunger operatively connected with the 115 drum for movement toward and from the surface thereof, revoluble feed rolls operatively connected with the drum for advancing a strip of stamps toward the path of the plunger, a revoluble absorbent moistening drum also operatively connected with the drum and having a hollow spindle, a source of water supply in communication with said spindle of the moistening roll, and a pressure roll for holding the stamps in contact with the moistening roll. 120

5. A stamp affixing machine having a revoluble drum, envelope feeding means for successively presenting envelopes to and arranging the same upon the surface of the 125 130

drum, clamping means for holding the envelope on the surface of the drum, a plunger operatively connected with the drum for movement toward and from the surface 5 thereof, means for supplying a strip of stamps, feed rolls operatively connected with the drum for feeding the stamps to present the same successively in the path of the plunger, means actuatable by the plunger 10 for successively severing the stamps from the strip, and stamp moistening means arranged in the path of the stamps as they are fed to the plunger, the envelope feeding means having an envelope engaging 15 reciprocably mounted finger, and a trip for successive engagement by tappets on the drum, an adjustable connection being provided between said trip and feed finger.

6. A stamp affixing machine having a 20 drum, means to supply mailing matter to the periphery of the drum, means operable to clamp said mailing matter to the drum, means to urge the latter means out of engagement with the mailing matter, and means

cooperating with the drum operable to af- 25 fix a stamp to the mailing matter.

7. A stamp affixing machine having a drum, means to supply mailing matter to the periphery of the drum, a clamp means, a cam operable to move said clamp means 30 against the mailing matter, a spring to normally urge the clamp means away from the mailing matter, and means cooperating with the drum operable to affix a stamp to the mailing matter.

8. A stamp affixing machine having a drum, a tappet on said drum, trip means operable by said tappet to feed mailing matter to the periphery of the drum, and means operable to affix stamps to the mailing mat- 40 ter while on the periphery of the drum.

In testimony whereof we affix our signatures in presence of two witnesses.
